BATHTUB

George H. Lochman, Winchester, Mass.

Application November 5, 1936, Serial No. 109,289

11 Claims. (Cl. 4—173)

The present invention relates to bathtubs and the like, and has for its object the provision of a bathtub having an integrally formed non-slip surface of improved construction and arrangement.

5 It is well known that the bottom of the conventional bathtub, shower bath and the like is slippery when wet, and particularly so if it or the feet of a user are at all soapy. Countless injuries occur as a result of falls by persons slipping while 10 standing or getting into or out of the tub.

Many attempts have been made to eliminate this danger. Various types of mats as rubber or other material have been devised which, when placed in the tub, provide a roughened or non-slip surface upon which the bather may stand. Such mats, however, are objectionable in that they may slip relative to the tub, and are unsightly and unsanitary, being difficult to keep clean.

It has also been proposed to form a portion 20 of the bottom of a bathtub with large transverse ridges or corrugations. Such ridges do not, however, prevent slipping in a direction lengthwise of the ridge when getting into and out of the tub, since the surface is smooth in that direction. 25 Such ridges are also objectionable because of the discomfort they cause to the bather as he stands upon them. A further objection arises from the fact that the ridges interfere with the drainage of the tub and are difficult to keep it clean.

30 The present invention avoids these objections and provides a bathtub having a non-slip surface integrally formed therein which effectively prevents slipping in any direction whatsoever, both when standing or moving about in the tub 35 or getting in or out, has no portions raised above the general level or surface of the bottom of the tub to cause discomfort to the bather, and which is self draining and, therefore, sanitary and easily cleaned.

40 More specifically, the present invention contemplates a bathtub or the like having a bottom surface provided with a plurality of small depressions or recesses large enough and of a shape to prevent slipping in any direction, and yet not so 45 large as to cause discomfort to the bather, and spaced sufficiently close together so that the foot of the bather will cover several of them, and provided with drainage channels to prevent the retention of bath water when the tub is emptied 50 after use.

In the drawing which illustrates the preferred embodiment of the present invention as embodied in a bathtub, Fig. 1 is a top plan view of a tub having a portion of its bottom formed with the 55 novel non-slip surface; Fig. 2 is a sectional end

view on a somewhat larger scale taken on the line 2—2 of Fig. 1; Fig. 3 is a fragmentary sectional view on a still larger scale taken on the oblique line 3—3 of Fig. 1; and Fig. 4 is a view similar to Fig. 3 but at right angles thereto, and taken on the oblique line 4—4 of Fig. 1.

The bathtub illustrated is of conventional shape, and is provided with the usual drain pipe 6 at one end. The bottom of the tub slopes gradually toward this end, and is also downwardly 10 inclined or curved transversely toward the middle, as shown in the sectional view, Fig. 2.

The non-slip surface comprises shallow circular depressions 8 interconnected by drainage channels 10, and is formed integrally with the tub by 15 casting. The non-slip area occupies somewhat over one-half the bottom area of the tub, adjacent the outlet end, and provides an area upon which the bather may stand or safely step when using or entering or leaving the tub.

The drainage channels 10 run diagonally from the outside rows of depressions downwardly toward the center and outlet end, connecting with a central channel 12 which leads directly to the outlet pipe opening. This arrangement and orientation of the channels insures that each and every depression or recess will be completely drained 25 when the tub is emptied.

The depressions are spaced at intervals sufficiently close so that several will be engaged by the 30 feet of the bather. While a single depression might not be sufficiently effective to prevent slipping under all circumstances, the cumulative effect of several such depressions affords substantially positive engagement with the feet to afford 35 complete safety to the bather.

The depressions are of a size large enough to prevent slipping and yet not so large as to be uncomfortable to the bather. Due to their symmetrical shape they are effective in all directions. 40 A satisfactory form of recess has been found to be cup-shape of about one-half inch diameter and one-eighth inch depth.

The channels, while designed primarily for drainage purposes, also provide a supplementary 45 non-slip surface because of their inclined or oblique arrangement tending to prevent slipping both longitudinally and transversely of the tub and being particularly effective adjacent the middle thereof where the feet of a bather may cover 50 channels at right angles to each other.

The channels need not be wide enough to be noticeable to the bather and yet effectively drain the depressions when the tub is emptied. It has been found that it is sufficient if the chan- 55

nels are one-eighth of an inch wide and one-eighth of an inch deep, that is, as deep as the recesses.

While the present invention has been illustrated and described in connection with a bathtub, it is to be understood that it is not limited to use in such construction but may be employed in shower baths, bathing pools, or any other structure where a person stands or walks bare footed on a wet surface. Where in the claims, therefore, reference is made to a bathtub, this is to be taken to include such other structures in which the present invention is adapted to be used.

15 The nature and scope of the invention having been described, what is claimed is:

1. A bathtub or the like having a bottom provided with an imperforate, non-slip top surface comprising a plurality of recesses spaced 20 apart less than the width of the human foot.

2. A bathtub or the like having a bottom provided with an imperforate, non-slip top surface comprising a plurality of small, cup-shaped recesses spaced apart less than the width of the 25 human foot.

3. A bathtub or the like having a bottom provided with an imperforate, non-slip top surface comprising a plurality of small, cup-shaped recesses so spaced as to bring several of the recesses beneath the foot of a user.

4. A bathtub or the like having a bottom provided with a non-slip top surface comprising a plurality of small recesses and channels of less width than the recesses for draining the same.

35 5. A bathtub or the like having a bottom provided with a non-slip top surface comprising a plurality of small recesses so spaced as to bring several of the same beneath the feet of the user, and narrow channels of less width than the recesses extending to the bottom of the recesses for draining the same.

6. A bathtub or the like having a bottom provided with a non-slip top surface comprising a plurality of recesses, a main channel extending

lengthwise of the tub, and a series of diagonal channels extending from the recesses to the main channel for draining the recesses.

7. A bathtub or the like having a bottom provided with a non-slip top surface comprising a 5 plurality of small recesses arranged in diagonal rows and connected by diagonal drainage channels.

8. A bathtub or the like having side walls and a bottom with an outlet at one end, the bottom 10 being provided with a non-slip top surface comprising two series of recesses arranged in diagonal rows and channels connecting the recesses of each row and extending from adjacent the side walls of the tub diagonally toward the 15 middle and the outlet end of the tub.

9. A bathtub or the like having a bottom provided with a draining outlet at one end and with a non-slip top surface extending in length from substantially the outlet end to a point beyond 20 the middle of the tub, and in width substantially from side to side of the tub, said surface comprising a plurality of imperforate, small recesses spaced apart less than the width of the 25 human foot.

10. A bathtub or the like having a bottom provided with a draining outlet at one end and with a non-slip top surface comprising a plurality of small recesses so spaced as to bring several of the same beneath the feet of the user, and narrow channels connecting the bottom of the recesses and extending obliquely toward the longitudinal middle of the bottom of the tub and toward the outlet end.

11. A bathtub or the like having a draining 35 outlet at one end, the bottom of the tub being provided with a non-slip surface adjacent the outlet, and a smooth surface distant from said outlet, the non-slip surface comprising a plurality of imperforate, small recesses so spaced 40 as to bring several of the same beneath the feet of the user, and channels for draining the recesses.

GEORGE H. LOCHMAN.
